THREE POSITION, SNAP ACTION
ROTARY SWITCH

Gerald P. Hermann, Pittsfield, Mass., assignor to General
Electric Company, a corporation of New York
Filed Jan. 24, 1962, Ser. No. 168,479
8 Claims. (Cl. 208—63)

This invention relates to snap acting switches, and, more particularly, to switches which are provided with a three position, snap action which find special utility in a distribution loop feed system.

In recent years, distribution systems for distributing electrical power to consumers have changed in many respects. Among these changes has been the increased usage of a type of distribution system which has been termed the loop feed system. In this system a plurality of distribution transformers are connected in an opened loop to a source of electrical power. In such loop feed systems each distribution transformer is provided with two energized power lines. Thus, when one distribution transformer or cable section develops a fault which requires its removal, the remaining distribution transformers in the loop system can still be energized. Further, if a section of the loop circuit should become open, the distribution transformers on each side of such section can still be connected to an energized line. This will be evident to those skilled in the art, since it will be obvious that even if one portion of the loop to the distribution transformers should become open, that the other portion of the loop would still conduct electrical power to the various distribution transformers connected to that portion of the loop feed system.

One problem which has arisen in use of loop feed systems is the need of a means for removing a transformer from the line when desired, or a means for sectionalizing a portion of the loop feed system. Sectionalizing, as used herein, means to isolate a portion of the loop feed system which connects two adjacent transformers in the system. For example, when it is desired to remove a transformer from the line, for inspection or repairs or for changeout, it is desired that the energized lines to the distribution transformers be de-energized before work is begun on the distribution transformer. Further, when it is desired to inspect the wire or cable, or to replace the wire or cable which connect two distribution transformers of the system, it is desirable that this portion of the line be de-energized, that is, that the particular section of power cable between two transformers be sectionalized by removing it from the source of power. To perform the above functions, either the transformer must be disconnected from the two energized lines or the line which is connected to two transformers must be disconnected from each of the transformers. It is preferred that this disconnection be accomplished by a switching means at each transformer. However, with presently available switches it has generally been found necessary to provide each transformer with two, two position switches. Each switch connects the transformer to, or disconnects the transformer from, one of the energized lines. It will be readily apparent to those skilled in this art that it is desirable to provide only a single switch in each transformer, such switch being able to function so as to connect the transformer to both energized lines or to disconnect the transformer from either energized lines, as desired. As can be seen, this requires a three position switch. Obviously, a single three position switch would require less space in the transformer and would generally be less costly than the two switches generally used in the art.

It is, therefore, one object of this invention to provide a novel, three position switch.

Another object of this invention is to provide a three

2

position switch for a transformer to enable disconnecting of the transformer from either of two energized lines, and to allow the connection of the transformer to both energized lines.

5 A further object of this invention is to provide a novel, three position switch for use in a distribution transformer loop feed system.

It will be understood by those skilled in this art that the lines used to energize the various transformers of a loop feed system will carry a large quantity of electrical power, generally the sum of the load of the various transformers connected to the loop. Opening the contacts of a switch carrying a large amount of electrical power will, of course, draw a substantial arc between the opening contacts. Clearly, it is desirable that a switch to open contacts on a large quantity of electrical power be provided with a snap action during opening of the contacts in order to break any arc which is formed during opening of the contacts. Further, a snap action is desired on the closing of the contacts of the switch to prevent pitting of such contacts and to prevent the welding of the contacts should they be closed on a fault.

It is, therefore, another object of this invention to provide a novel three position switch having snap action both in opening and closing of all contacts.

Briefly, this invention in a preferred form thereof, comprises an actuating member which is movably secured to a mounting member. Two movable switch means are pivotally mounted on the mounting member and movable into and out of engagement with two energizable switch contacts. Spring means are provided secured to the switch means for aiding in moving the switch means in opening and closing of the contacts. Further, means are provided connected between the switch means and the actuating member, whereby in one position of the actuating member both switch means engage the contacts, while in a second position of the actuating member one of the switch means is disengaged from one of the contacts, while in a third position of the actuating member the other switch means is disconnected from the other contact. In another embodiment of this invention the positions of the actuating member correspond to the condition of the switch in which both contacts are opened, or in which either contact is closed.

45 The invention which is sought to be protected will be clearly pointed out and distinctly claimed in the claims which are appended hereto. However, it is believed that the full scope of this invention, as well as the manner in which its various objects and advantages are obtained, as well as other objects and advantages thereof, will be more fully understood from the following detailed description of a preferred embodiment thereof, especially when considered in the light of the accompanying drawings, in which:

50 FIGURE 1 is a perspective view of one form of a three position, snap acting switch, according to this invention;

55 FIGURE 2 is a perspective view similar to FIG. 1 showing the switch in another position;

60 FIGURE 3 is a fragmentary plan view, partly in section, showing a modified form of switch, according to this invention;

65 FIGURE 4 is a sectional view taken on the line 4—4 of FIG. 3;

FIGURE 5 is a schematic representation of a loop feed distribution system; and

FIGURE 6 is a plan view of another type of three position switch made according to this invention.

Referring now to the drawings, in which like numerals are used to indicate like parts throughout the various views thereof, there is shown a novel three position, snap acting switch according to a preferred embodiment of

this invention. This novel three position, snap action switch finds special utility in a loop feed distribution system, such as is shown schematically in FIG. 5. Referring first to FIG. 5, the loop feed system is shown as comprising a plurality of distribution transformers connected in an open loop to a source of electrical power, such source being designated 10. As shown, the loop feed system from source 10 is open between transformer 12 and transformer 14. The distribution transformers are shown as being serially connected to the power source 10, four on one side of the open section and three on the other side. Thus, all the distribution transformers are energized by the source 10. Should one of the distribution transformers develop a fault, such that it must be removed from service, for example, distribution transformer 12, then it can be seen that the distribution transformers 14, 16, and 18 will still be energized from source 10 by means of the line 20; while the distribution transformers 22, 24, and 26 will still be energized by line 28 from the source 10. To remove distribution transformer 12 from the line, it is necessary to provide some disconnecting means to disconnect line 30 between distribution transformers 12 and 14, (presently shown as open at transformer 12) and also to disconnect line 32 between the transformers 12 and 22. To obtain this desired disconnection, it is clearly desirable that only a single switch means be provided in each distribution transformer. Also, it is desirable that the disconnection be made from the adjacent transformers to prevent a live lead being in the disconnected transformer. In the above example a switch in transformer 14, shown schematically as switch 34, may be used to disconnect 14 from line 30, while a switch 36 in transformer 22 may be provided to disconnect transformer 22 from the line 32. This would of course effectively remove transformer 12 from electrical power and allow repairs or change-outs to be performed on transformer 12 without in any manner disturbing the energization of the other distribution transformers in the system. Further, where it is desirable to disconnect line 30 between transformers 12 and 14 such that line 30 may be inspected, or replaced if necessary, then clearly switch 38 in transformer 12, disconnecting transformer 12 from line 30, and switch 34 in transformer 14, disconnecting transformer 14 from line 30, would provide the desired sectionalizing of the line 30, to effectively remove it from service without in any manner disturbing the energization of all the distribution transformers in the loop feed system. The novel three position, snap action switch of this invention is uniquely designed for use in the above type system. However, it will be apparent from the following description that the three position, snap acting switch of this invention is not limited to use in a loop feed system.

Considering now FIGS. 1 and 2 of the drawing, a preferred embodiment of the novel, three position, snap action switch of this invention will be described in detail. As shown, the three position, snap acting switch comprises an actuating member, such as crank 40, which is movably secured to a mounting member 42. Mounting member 42 may be secured within a transformer or other enclosing means (not shown) or it may be a portion of a wall of a transformer tank or other enclosing means. In the preferred embodiment shown, two pairs of movable contacts 44 and 46 are provided, being pivotally mounted on the mounting member 42, in a manner to be described, and movable into and out of engagement with fixed contacts 48 and 50, respectively. A spring means 52 is secured between the movable contacts 44 and 46 to aid in moving said contacts into and out of engagement with fixed contacts 48 and 50, in a manner which will be hereinafter more fully described. Connecting means 54 and 56 are provided connected between the movable contacts 44 and 46, respectively, and the actuating member 40, for moving the movable con-

acts into and out of engagement with the fixed contacts 48 and 50.

Considering specifically FIG. 1 of the drawing, a preferred embodiment of the novel three position, snap acting switch of this invention is shown in its closed position, whereby movable contact 44 engages fixed contact 48 and movable contact 46 engages fixed contact 50. In this position, the actuating member 40 is in the closed position, as shown, and the connecting means 54 and 56 are in a substantially vertical position. As shown, the actuating member 40 is pivotally connected to the mounting member 42 by means of a shaft 58 which extends through the mounting member which may be, for example, the tank of a distribution transformer, to an actuating handle 60. As will be well understood by those skilled in the art, the three position, snap acting switch may be installed inside of a distribution transformer with the actuating handle 60 on the exterior of such transformer, whereby it may be readily manipulated either by means of a switch stick, or by hand, as desired. Of course, if desired, an indicator may be provided with operating handle 60 to indicate the position of the switch.

The movable contacts 44 and 46 are shown in the form of a pair of blade members which are pivotally mounted to a central terminal block 62 by bearing means 64 and 66, respectively. Terminal block 62 is mounted on an insulating member 68 which is secured by means of screws 70 to straps 72. Straps 72 are bolted to conductors 74 which are mounted in bushings 75. The bushings 75 are secured to the mounting member 42, thus holding the straps 72 and other portions of the switch in spaced relation with the mounting member 42 and insulated therefrom. As shown, the bottom portion of terminal block 62 is provided with a terminal means 76 for connection to electrical apparatus, such as for example, the high voltage side of a distribution transformer.

The switch blades 44 and 46 are provided with a biasing means in order to form a tight electrical connection between the switch blades and the stationary contacts. The biasing means is in the form of a pin or bolt member 78 which extends through the switch blades and is provided on each end thereof with a compression spring 80 which forces the switch blades towards each other. In this manner, as the switch blades, for example the switch blades 44, close on the fixed contact 48 the blades are firmly forced against the fixed contact 48 to provide a good electrical connection between the blades 44 and the contact 48. Further, it will be understood that by means of the compression springs 80 the switch blades 44 are forced into a firm friction fit with the fixed contact 48 requiring a given amount of force to overcome such friction in opening the movable contacts 44 from the fixed contact 48. As can be seen, the outer portion of the bolts 78 are provided with securing means 82 about which the tension springs 52 are connected. As can be seen from this view of the drawing, each of the movable contacts 44 and 46 are pivoted to the terminal block 62 about the points made by the bearings 64 and 66. It will be seen that in the closed position each tension spring 52 is below this point of contact, thereby providing an over center means to aid in holding the movable contacts 44 and 46 in their closed positions on the fixed contacts 48 and 50, respectively. While two springs 52 are shown as used with movable contacts 44, 46, it will be understood that a single spring could also be used.

Considering now the connecting means 54 and 56 which connect the movable contacts 44 and 46 to the actuating member 40, it can be seen that each of the connecting means are in the form of two rods, one being an insulating member 84 and the other being an insulating or metallic channel member 86. Each insulating member 84 is connected to one of the movable contacts 44 or 46 by means of the pin member 78 which is provided

with the biasing compression springs 89. The two members of each of the connecting means 54 and 56 are rigidly connected together at their ends by means of pin members 88. The connecting members 86 are in the form of channels and within each of the channels is mounted a spring 90. Each of the springs 90 is connected between the pin 88 and a connecting bearing 92. The bearing 92 connects each of the connecting means 54 and 56 to the opposite sides of the actuating member 40, as shown. Further, each of the channels 86 is provided with a slotted opening 94 through which the bearing 92 extends and in which it is movable during operation of the actuating means 40. In the closed position shown in FIG. 1, both of the springs 90 are in compression, forcing the movable contacts 44 and 46 in a downward position in contact with the fixed contacts 48 and 50.

Referring now to FIG. 2, when the actuating member 40 is rotated clockwise, in order to disconnect movable contact 46 from fixed contact 50, it will be apparent that the spring member 90 of connecting means 56 is placed in tension, being stretched within the channel 86 between connecting points 88 and 92. The stretching of the spring 90 stores energy which is suddenly released, when the force of the spring 90 overcomes both the friction between the movable contact 46 and fixed contact 50 and the over center force of springs 52, to thereby snap the movable contact 46 open from fixed contact 50. It will be understood that a similar snap action will be obtained even with built contacts having a negligible friction force due to the over center force of springs 52. Of course, it will be apparent, that as the movable contact 46 begins to move upward from the fixed contact 50 that the tension springs 52 are moved to a position on the other side of the center point formed by the pivot bearing 66 and thereby aid in urging the movable contacts 46 to the open position shown. As the actuating member 40 is rotated, in this instance in a clockwise direction, to disengage contacts 46 from fixed contacts 50, it will be seen that the spring within the channel 86 on the movable contact 44 is placed in greater compression, thereby more firmly holding contact 44 on fixed contact 48. In this manner it can be seen that in one position of the actuating member, one movable contact is separated from its fixed contact with a snap action, while the other movable contact is more firmly held in its closed position. As will be apparent, the slot members 94 may be designed such that the initiation of the opening or closing operation may be caused by one of the bearings 92 pressing against one end of the appropriate slot.

Still referring to FIGS. 1 and 2, it will be apparent that, as the actuating member 40 is moved in a counter clockwise direction, from the position shown in FIG. 2 to the position shown in FIG. 1, the spring 90, associated with movable contact 46, is forced downwardly by the connecting bearing 92 storing energy in compression until such time as the torque or force applied to contact 46 by spring 90 is sufficient to overcome the tension, torque or force of the springs 52. At this point, contact 46 begins to close on contact 50 with the snap action of the stored energy in the spring 90. At the same time, as springs 52 begin to move downwardly with movable contact 46 they will reach the over center point with reference to the bearing means 66, and will then add their energy in firmly closing contact 46, with a snap action, onto the fixed contact 50. Thus it can be seen, that by means of the novel three position switch of this invention means are provided for snap action in both opening and closing of the contacts of the switch means. It should also be apparent that, by means of the springs 90 and 52, a snap action is provided in both opening and closing of the contacts without regard to the speed of moving the operating handle 60.

Of course, it will be obvious that if the actuating member 40 is moved further in a counter clockwise position

from the position shown in FIG. 1, that a reverse action will take place, similar to that described for the clockwise motion in FIG. 2, whereby contact 44 will be removed from fixed contact 48. Thus, it will be apparent, that by means of the three position snap acting switch of this invention a switch is provided in which both contacts of the switch may be closed or either of the switch contacts may be opened. As shown in FIG. 1, both contacts of the switch are closed. As shown in FIG. 2, contact 44 is closed on contact 48, while contact 46 has been disconnected from contact 50. In the third position of the switch (not shown), contact 44 will be disengaged from contact 48, while contact 46 will be engaged with contact 50.

As shown in FIGS. 1 and 2, stop means are provided in the form of bosses 95 on the insulated rods 84 to prevent the movable contacts 44 and 46 from being opened too far during their opening sequence. In the same manner, stop means are provided in the form of washers 98 about the screw means 100, such that the lower ends of the movable contacts 44 and 46 will contact the stop means 98 to prevent the switches from closing too far on the fixed contacts 48 and 50. The screw means 100 are utilized to secure the fixed contacts 48 and 50 to the insulated member 68. Of course, screws 100 also aid in securing straps 72 to the insulated member 68. It will also be apparent to those skilled in this art that each of the fixed contacts 48 and 50 is provided with terminal means, which may be, for example, the conductors 74, for connecting each of the fixed contacts 48 and 50 to an energized line conductor. Thus, the power to the electrical apparatus, for example, a transformer, is brought in from energized line conductor (not shown) through a fixed contact 48 and movable contact 44 to the terminal block 62 and thence from terminal 76 to the electrical apparatus. In the same manner, the electrical energy is carried from a second electrical conductor (not shown) to the fixed contact 50 and then through the movable contacts 46 to the terminal block 62 and the terminal 76 to the desired electrical apparatus.

Referring now to FIGS. 3 and 4 of the drawing, a modification of the switching means shown in FIGS. 1 and 2 is disclosed. The connecting means 54 and 56 are the same as hereinbefore described, with reference to FIGS. 1 and 2. However, in this modification the fixed contacts are in the form of clamp or jaw members 102 which fit within an explosion pot 104, the explosion pot being secured to an insulated mounting member 106. Of course, the second fixed contact similarly is provided with jaw members 108 within the explosion pot 110 which also is firmly secured to the insulated mounting member 106. Jaw members 102 and 108 are connected by means of metallic straps 112 and 114, respectively, to a terminal member 116 and 118, respectively, to which the energized lines (not shown) may be connected. The terminal board 120, to which the movable contacts 122 and 124 are connected, is also firmly attached to the insulated mounting member 106. Explosion pots 104, 110 are attached to terminal board 120, as by the extensions 121, and may also be secured to the mounting member 106 in any desired manner, such as by gluing.

As shown, specifically in FIG. 3, the movable contacts 122 and 124 are pivoted to the terminal board 120 by means of the pivot bearings 126, 128 respectively. In this embodiment, the movable contacts 122 and 124 are in the form of curved bayonet contacts, which fit within the explosion pot 104 and 110 and make firm electrical connection with the jaw members 102 and 108, respectively. As can be seen, a tension spring 130 is secured to the pivoting arms 132-134 of the movable contacts by the connecting bosses 136 and 138 respectively. A plate member 140 may be secured to terminal board 120 by bolt members 142. Of course, either bolt members 142

may act as the terminal for the electrical apparatus. In order to insure a good electrical connection between movable contacts 122, 124 a braided wire 144 may be provided, electrically connected to both movable contacts 122, 124 and the plate member 140, as shown.

In FIG. 3, it can be seen that the position of the contact members of the switch are in the same position as shown in FIG. 2, that is, contact member 122 is disengaged from contact 102, while contact member 124 is engaged with contact 108. Thus it will be apparent that the position of the actuating member 40 and the connecting means 54-56 will be in the same position as shown in FIG. 2. Clearly, the operation of the modification shown in FIGS. 3 and 4 is exactly the same as that for FIGS. 1 and 2. The spring 130 performs the identical function in opening and closing of the contacts as the spring 52 in FIGS. 1 and 2. However, as will be apparent to those skilled in the art, one of the advantages of this modification is that as the movable contacts are withdrawn from the fixed contact the arc which is drawn upon opening of the contact is drawn within the explosion chambers 104 and 110, and the arc is extinguished therein, in a manner well understood by those skilled in this art.

In FIG. 6, a second embodiment is shown, in which a three position switch is provided, having a position in which both switch contacts are opened. In the embodiment shown in FIG. 6, the switch is very similar to that described in detail with reference to FIGS. 1 and 2. Like numerals will be used to indicate similar parts in FIG. 6, followed by the letter *a*.

Considering now FIG. 6, an actuating member is provided, in the form of a crank 40a, which is movably secured to a mounting member 42a by means of a shaft member 58a. As noted, with reference to FIGS. 1 and 2, mounting member 42a may be the tank of a transformer, or the wall of any suitable enclosure, or it may be secured within a transformer or any suitable enclosure. In this embodiment movable contacts 44a and 46a are provided, pivotally mounted on terminal board 62a which may be secured to mounting member 42a in the same manner as described with reference to FIGS. 1 and 2, and movable into and out of engagement with fixed contacts 48a and 50a. Spring means 52a are provided, connected between the movable contacts 44a and 46a. Spring means 52a aids in moving contact 44a into and out of engagement with fixed contact 48a. Connecting means 54a and 56a are provided, connected between movable contacts 44a and 46a, respectively, and the crank member 40a, for moving contacts 44a and 46a into and out of engagement with fixed contacts 48a and 50a, respectively.

As can be seen from FIG. 6, and the above description, this embodiment is similar to the embodiment shown in FIGS. 1 and 2, and hereinbefore described in detail. The main difference is in crank member 40a, which is 180° reversed from member 40, and in the terminal board 62a which is designed to enable the pivotal connection of movable contacts 44a, 46a to be further removed from fixed contacts 48a, 50a. Further, stop means 96a are provided on the terminal board 62a to prevent movement of one movable contact when the other movable contact is being moved to an open or closed position. In view of the earlier description of FIGS. 1 and 2 it is not believed that any further detailed description of FIG. 6 is necessary. However, the operation of this modification of the three position switch will be described.

As shown in phantom lines in FIG. 6, the switch is in its open position, with contact 44a removed from contact 48a and contact 46a removed from contact 50a. As can be seen, spring means 52a are in tension, holding contact 44a against one stop 96a, and contact 46a against the other stop 96a. The springs 90a, within the channel members 86a of the connecting means 54a and 56a are slightly in tension, also holding contacts 44a and 46a against stops 96a. If the crank member 40a is now

rotated clockwise to the position shown in full lines in FIG. 6, it can be seen that spring 90a in connecting means 54a is placed in compression, storing energy, which is suddenly released when the force of spring 90a overcomes the tension force of spring means 52a, thereby snapping movable contact 44a into closed position with contact 48a. As movable contact 44a begins to close the spring means 52a moves below the pivot point 64a of contact 44a, to thereby provide a tension force to aid in snapping movable contact 44a in closed position with contact 48a. Thus it can be seen that the spring means 52a acts as an over center spring in the same manner as spring means 52, of FIGS. 1 and 2. At the same time, the spring 90a in connecting means 56a is placed in slightly greater tension, holding movable contact 46a more firmly against the stop 96a.

Movement of the actuating member 40a in a counter-clockwise direction, from the position shown in full lines in FIG. 6 to the position shown in phantom lines, will open contacts 44a and 48a. In moving counterclockwise, spring member 90a in connecting means 54a will be placed in tension, storing energy until the force in spring 90a is sufficient to overcome any friction between contacts 44a and 46a and the tension in spring means 52a. When the force in spring 90a is sufficient, the stored energy is released, snapping movable contact 44a away from contact 48a. It will be apparent that spring means 52a aids in moving contact 44a to its open position after it passes to the other side of the center or pivot point 64a. As the actuating member moves in a counterclockwise direction to separate contacts 44a and 48a, the spring 90a in connecting means 56a will release the additional tension placed in spring 90a during the closing operation. However, spring 90a will still be in tension, and tension will also be applied to contact 46a by spring means 52a. Thus, movable contact 46a will remain in its open position, substantially against the stop member 96a. Of course, it will be readily apparent that the operation of the switch is substantially the same as that detailed above, for the closing and opening of the contacts 46a and 50a.

From the above detailed description of a preferred embodiment of this invention and modifications thereof, it will be apparent to those skilled in the art that there has been described a novel, three position snap acting switch which may be particularly useful in loop feed distribution systems. However, it will also be apparent that the novel three position snap acting switch of this invention may be used in many other types of systems whenever it is desired to provide a switching means wherein the contacts may be both closed or both opened and either of the contacts may be opened, as desired. While preferred embodiments of this invention have been described in detail in accordance with the patent statutes, it will be understood that many modifications may be made in the construction and materials of the switch without departing from the spirit and scope of the invention hereinbefore set forth. Obviously, all such modifications are included as fall within the scope of the invention, as defined in the claims appended hereto.

What is claimed as new and which it is desired to secure by Letters Patent of the United States is:

1. A three position snap acting switch comprising, a mounting member, an actuating member movably secured to said mounting member, a pair of movable contacts and a pair of fixed contacts, said fixed contacts being secured to said mounting member, each of said fixed contacts being provided with a terminal for connection to an energized line, each of said movable contacts being individually pivotally mounted on a terminal block, said terminal block being secured to said mounting member, connecting means individually connecting each of said movable contacts to said actuating member for individually moving either of said movable contacts into and out of engagement with one of said fixed contacts, spring means connected between said movable contacts in over

center position, whereby said spring means aid in closing either of said contacts during closing and aids in opening either of said contacts during opening.

2. A three position snap acting switch comprising, an actuating member, a pair of movable contacts and a pair of fixed contacts, said fixed contacts being secured to an insulated mounting member and being provided with terminals for connection to an energized line, each of said movable contacts being individually pivotally mounted on a terminal block, said insulated mounting member being secured to said terminal block, connecting means individually connecting each of said movable contacts to said actuating member for individually moving either of said movable contacts into and out of engagement with one of said fixed contacts, spring means connected between said movable contacts in over center position, whereby said spring means aid in closing either of said contacts during closing and aids in opening either of said contacts during opening.

3. A three position, snap acting switch comprising an actuating member, a pair of fixed contacts, a pair of movable contacts, each of said fixed contacts being provided with a terminal, a terminal block, each of said movable contacts being individually pivotally mounted on said terminal block, an insulating member secured to said terminal block, said fixed contacts secured to said insulating member, connecting means individually connecting each of said movable contacts to said actuating member, said connecting means being provided with springs, and spring means connected between said movable contacts, whereby movement of said actuating member operates through said springs and said spring means to move each of said movable contacts individually into and out of engagement with one of said fixed contacts.

4. A three position snap acting switch comprising an actuating member, a pair of fixed contacts, a pair of movable contacts, each of said fixed contacts being provided with a terminal, a terminal block, said movable contacts being pivotally mounted on said terminal block, an insulating member secured to said terminal block, said fixed contacts secured to said insulating member, connecting means connecting each of said movable contacts to said actuating member, said connecting means being provided with springs, said springs in said connecting means being connected between said connecting means and said actuating means such that movement of said actuating member from a mid position will cause one of said springs in one of said connecting means to be placed in compression while the other of said springs in the other of said connecting means will be placed in tension, and spring means connected between said movable contact whereby movement of said actuating member operates through said springs in said connecting means and said spring means to move said movable contacts into and out of engagement with said fixed contacts.

5. A three position snap acting switch comprising a

mounting member, an actuating member movably secured to said mounting member, a pair of movable contacts and a pair of fixed contacts, said fixed contacts being secured to said mounting member, each of said fixed contacts being provided with a terminal for connection to an energized line, each of said movable contacts being individually pivotally mounted on a terminal block, said terminal block being secured to said mounting member, connecting means individually connecting each of said movable contacts to said actuating member for individually moving each of said movable contacts into and out of engagement with one of said fixed contacts, springs in said connecting means and connected at one end to said actuating member, spring means connected between said movable contacts in over center position, whereby said spring means cooperate with said connecting means to aid in closing said contacts during closing and aid in opening said contacts during opening.

6. A three position snap acting switch comprising, an actuating member, a pair of movable contacts and a pair of fixed contacts, said fixed contacts being secured to an insulated mounting member, each of said fixed contacts being provided with a terminal for connection to an energized line, said movable contacts being pivotally mounted on a terminal block, said insulated mounting member being secured to said terminal block, connecting means connecting each of said movable contacts to said actuating member for moving said movable contacts into and out of engagement with said fixed contacts, spring members mounted in said connecting means, one end of each of said spring members connected to said connecting means, the other end of each of said spring members connected to said actuating member, spring means connected between said movable contacts in over center position, said spring means providing opposition to said spring members during a portion of the movement of said movable contact to provide snap acting movement of said movable contacts.

7. A three position switch as claimed in claim 6 in which said movable contacts are in engagement with said fixed contacts in one position of said actuating member, movement of said actuating member from said one position causing one of said movable contacts to be disengaged from one of said fixed contacts.

8. A three position switch as claimed in claim 6 in which said movable contacts are disengaged from said fixed contacts in one position of said actuating member, movement of said actuating member from said one position causing one of said movable contacts to engage one of said fixed contacts.
